UNITED STATES PATENT OFFICE

100,091

DESIGN FOR A HEATER

Kenneth H. Daegling, Whiting, Ind., assignor to
The Moore Corporation, Joliet, Ill., a corporation of Delaware

Application October 11, 1935, Serial No. 58,953

Term of patent 3½ years

To all whom it may concern:

Be it known that I, Kenneth H. Daegling, a citizen of the United States, residing at Whiting, county of Lake, and State of Indiana, have invented a new, original, and ornamental Design for a Heater, of which the following is a specification, reference being had to the accompanying drawing, forming a part thereof:

In the drawing:

The figure is a perspective view showing the front and one side of a heater embodying my design, the other side being like the one shown.

I claim:

The ornamental design for a heater, as shown and described.

KENNETH H. DAEGLING.
